CAR ROOF

Edwin G. Franck, Detroit, Mich., assignor to
 Hutchins Car Roofing Company, Detroit, Mich.,
 a corporation of Delaware

Application March 26, 1934, Serial No. 717,504

3 Claims. (Cl. 108—5.4)

The invention relates to car roofs of the rigid type in which the roofing sheets are held in fixed relation to each other and the invention consists in the peculiar construction as hereinafter set forth.

In the drawing:

Fig. 1 is a plan view of a portion of the roof;

Fig. 2 is a cross section thereof;

Fig. 3 is a section longitudinally of the roof; 10 and through one of the carlines;

Fig. 4 is a side elevation of a portion of the roof.

A are the side plates of the car frame and as shown are Z bars having horizontally extending 15 web portions with downturned flanges at their inner ends. B are carlines of inverted channel cross section with outwardly extending flanges B' at their lower ends, connected with the sides by rounding portions B². The depth of the channel is greatest in the ridge portion of the carline and tapers therefrom towards the eaves, the extra metal being used to progressively increase the width of the flanges B' towards the eaves. Thus the carline may be formed from a flat blank 20 having parallel edges.

Between the carlines B are roofing sheets C which extend from eaves to eaves and which are pressed to form upstanding flanges C', lying adjacent to the inner walls of the carline B. These 30 upstanding flanges are further provided at their upper ends with laterally extending flanges C² which overlap each other and lie adjacent to the web portion of the carline to which they are secured by rivets D. These rivets may also be 35 used for securing running board saddles E supported on the carlines. The upstanding flanges of the side plates A have curved portions A' around which the ends of the carlines are bent, the flanges B' lying adjacent thereto. The web 40 portion B³ is curved downward at the eaves and thus forms at its lower end an opening from the channel to the exterior of the car. To weatherproof this opening a flashing F is arranged within the channel, being secured at its inner end to 45 the web portion of the carline and at its outer end to the flange A' of the plate. The running boards G are mounted on the saddles E and are supported at the end of the car by brackets H and I.

With the construction as described, the flanges C' and C² of the roofing sheets form a reinforcement for the carlines which therefore may be made of lighter gauge metal than would otherwise be necessary. A single line of rivets D serves 5 to unite these flanges with the carlines, while the eaves ends of the sheets are secured to the plate A by riveting as indicated at J. The whole constitutes a rigid and thoroughly weatherproof structure.

What I claim as my invention is:

1. In a car roof, carlines of inverted channel cross section having laterally extending flanges at their lower ends, roofing sheets extending from eaves to eaves arranged beneath said carlines and having upwardly extending flanges for fitting against the inner sides of the carlines, and laterally extending overlapping flanges fitting against the web of the carline and secured thereto by riveting. 10

2. In a car roof, carlines of inverted channel cross section having laterally extending flanges at their lower ends, roofing sheets extending from eaves to eaves beneath said carlines and provided with upstanding flanges fitting the sides of the 25 carline and laterally extending overlapping flanges fitting against the web of the carline and being secured thereto by riveting, said carlines and sheets having downturned channel portions at their eaves end, side plates to which said downturned portions are secured and a flashing secured at its outer end to said side plate and its inner end to said overlapping flanges and web of the carline. 30

3. A car roof comprising side plates formed of metallic Z bars having upwardly extending flanges rounded to extend laterally inward, carlines and roofing sheets extending from eaves to eaves and having downturned eaves portions secured to said side plate flange by riveting, said carlines being of inverted channel cross section with outwardly extending base flanges and said roofing sheets having upwardly extending flanges fitting against the sides of the carline and laterally extending overlapping portions fitting against the web of the carline and secured thereto by riveting. 35

EDWIN G. FRANCK.
